LEONHARD VETTER, OF BAD HOMBURG, GERMANY, ASSIGNOR TO THE FIRM FEIN-APPARATE G. M. B. H., OF FRANKFORT-ON-THE-MAIN, GERMANY

TYPE-INKING DEVICE

Application filed April 25, 1929, Serial No. 357,983, and in Germany December 13, 1928.

My invention relates to an inking device for the types of typewriting and similar machines by means of an ink roll mounted on the machine in such a manner that it projects onto the path of the type rod or type lever and is thrown by the same against a pad impregnated with liquid ink from a reservoir. The ink roll takes the required amount of ink and transmits the same to the next following depressed type when the roll is returning to its initial position. The difficulty consists in maintaining a uniform impregnation of the ink pad in order that the ink roll is charged with always the same quantity of ink when striking against the pad so that only so much ink is securely transmitted onto the type as is necessary for the production of a clear copy. It is further important that the ink roll adjusts itself accurately to the centre of the type, and with this object in view the device is shiftable on its holder in horizontal direction. The ink reservoir must also be adjustably mounted on a holder in order that it may be uniformly used on any typewriting machine.

An essential characteristic feature of the invention consists in that the ink is supplied to the ink-pad in a quantity capable of being easily regulated. The regulation can go up to completely shutting off the supply of the ink to the pad, this taking place when the typewriting machine is not to be used.

An embodiment of the invention is illustrated by way of example in the accompanying drawing in which

Fig. 1 is a front elevation showing the type inking mechanism according to the invention.

Fig. 2 is a side elevation.

Fig. 3 is a top plan view.

Fig. 4 is a section on line 3—3 of Fig. 2.

On the guide plate α for the types having in its end a slot b as commonly provided in guide plates for typewriting machines having type bars and said plate being fixed by means of screws screwed through holes l , a plate d is fixed which has cheeks k . The guide plate α is overlapped by a plate g having longitudinal slots c and noses e , screws f

traversing said longitudinal slots c and holes of the plate d .

Because of the adjustability of the plate d this plate can be adjusted in accordance with the width of the guide plate α .

The top edge of plate d is bent at right angles and the horizontal arm d' which is thus formed ends in a lug j . With this lug j engages a pin i shiftable in longitudinal direction and adapted to be turned and to be secured in the adjusted position by means of screws m .

On the end of a pin i facing the guide plate α a head n is arranged in which a spindle o is mounted which serves as pivot axle for the ink roll r made of felt or any other liquid absorbing material. The ink roll r is rotatably mounted on a vertical pin s of a bow p, p' . In the horizontal arm of bow p holes are provided, with one of which the spindle o engages so that the bow p, p' can turn around the spindle o . A second bow q is rotatably mounted on said spindle o and has an upper arm q' which is offset and grips hook-like over the top end of the vertical pin s . A spring t wound around the spindle o has its upper end connected to the horizontal arm of the bow p and its lower end to the horizontal arm of the bow q so that the arm q' of this bow q is held permanently in engagement with pin s , as shown in Fig. 3.

The bow q has a handle h by means of which it can be oscillated in opposition to the action of spring t , when the ink roll r has to be removed from its carrying pin s , for instance in order to be interchanged.

A thin spiral spring v is wound around the head o' of the spindle o and fixed at the one end to the arm q' and at the other end to the head o' . This spring v is designed to return the ink roll r with the bows q, p into the initial position shown in Fig. 3. The spring v is not so strong as the spiral spring t so that the bow can be oscillated by hand for removing the ink roll r .

An ink reservoir w is mounted on the horizontal arm d' of plate d and fixed on this horizontal arm by means of a screw y guided in an oblong hole x of the horizontal arm d' as shown in Fig. 4. A pad z of felt or other

liquid absorbing material is jammed in an aperture of the wall of reservoir w , said reservoir being preferably of oval shape. A wick 1 is located in a channel u of the wall 5 of the reservoir w leading to the ink pad z , said wick projecting into the liquid ink in the reservoir.

A screw 2 traversing the wall of the reservoir w extends to the channel u and can be 10 screwed into this channel. The charging hole 4 of the reservoir w is closed by a stopping screw 3.

The operation is as follows: The depressed type guided on the guide plate a strikes 15 against the ink roll r and throws this ink roll, in opposition to the action of the spiral spring v , against the ink pad z so that the ink roll takes ink from the pad z to which the ink is supplied from the reservoir w by the wick 1, this ink being then transmitted to the depressed type (direction of arrow line in Fig. 3). The type, after having moved along the ink roll, returns to its initial position. This 20 operation is repeated at every depression of a type.

For removing the ink roll r the bow q, q' is oscillated in opposition to the action of the spiral spring t , as shown in dash lines in Fig. 3.

25 To accurately adjust the ink roll with regard to the reservoir w , the spindle o and the bow p, q can be slightly inclined after loosening of the screws m , together with the pin i which carries the spindle o (position shown in Fig. 2).

A finger 5 extending from the head n serves as abutment for the inclined ink roll. The free cross section of the channel u can be regulated by means of the screw 2, and by 40 strangling or releasing the wick 1 by means of said screw the passage of ink from the reservoir w to the ink pad z can be regulated.

I claim:—
45 A type inking device for typewriting and similar machines, comprising in combination an ink roll in the path of the depressed type, a spring-controlled holding bow carrying said ink roll and adapted to be oscillated in opposition to the action of its spring, a reservoir for liquid ink, and an ink pad projecting from said reservoir adapted to transmit ink to said ink roll upon the latter being thrown against said pad by the action of the 50 depressed type, an angular sheet metal plate having a lug on the free end of its horizontal arm and an oblong slot, a cheek adjustable on the vertical arm of said angular plate, a screw for fixing said ink reservoir adjustable 55 in said oblong hole of said horizontal arm, and a pin for carrying the holder for the ink roll adjustable in said lug.

60 In testimony whereof I affix my signature.
LEONHARD VETTER.
